2,040,048

METHOD OF TREATING HYDRO-CARBON OIL

Arthur C. Hampton, Belleville, N. J., assignor to
Gasoline Products Company, Inc., Newark,
N. J., a corporation of Delaware

Application May 10, 1933, Serial No. 670,218

7 Claims. (Cl. 196—48)

This invention relates to processes for the treatment of hydrocarbon oils and pertains more particularly to processes for the production of intermediate products such as Diesel fuel oil or 5 furnace oil, as a by-product in the formation of gasoline from heavier hydrocarbon oils.

Diesel fuel oil is generally accepted as having the following characteristics, approximately: Flash point, above 150° F.; bottom sediment and 10 water, less than .1%; carbon residue, less than .5%; insoluble in hexane, less than 5%. Furnace oil may have a gravity of about 38.2° A. P. I., an initial boiling point of 214° F. approximately, and an end point of about 500° F.

15 It is an object of my invention to provide a process whereby oil of these general characteristics may be made, as a separate product, in a conventional oil cracking unit adapted for the production of gasoline, without interfering seriously with the primary function of that unit.

This invention permits the simultaneous production of intermediate products such as Diesel fuel oil or furnace oil, and gasoline, even when the fractionating apparatus, adapted to segregate 25 the gasoline, is operated at relatively high pressure, such as those in excess of 100 pounds per square inch, for example, 200 pounds per square inch. Relatively high pressures in ordinary systems, of the type known heretofore, make it difficult, if not impossible, to obtain an intermediate 30 product directly from the fractionating system, having the necessary flash point to meet the usual specifications. In a great many cases it is impossible, or at best undesirable, to introduce 35 steam or water into the high pressure system in order to strip this intermediate cut of light ends.

In accordance with my invention relatively 40 heavy oil, such for example, as gas oil of Mid-Continent characteristics and having a gravity of about 34° A. P. I., is subjected to cracking of conventional intensity for the production of gasoline and other light distillates. The resulting cracked products are separated into vapors and an unvaporized residue, in an evaporating zone. The 45 residue is withdrawn to a tar flashing zone of lower pressure, wherein the lighter constituents thereof are vaporized and freed from residual tar, the latter product being withdrawn from the process. The lighter constituents mentioned are 50 subjected to fractionation in the upper portion of said flashing zone, which acts as a secondary fractionating zone, to produce relatively light and clean vapors, and reflux condensate which 55 mingles with the residual tar. The vapors separated in the evaporating zone are fractionated in

a primary fractionating zone with the resultant separation of light vapors in the gasoline boiling range, which are removed as a desired product, and reflux condensate.

During the treatment of the cracked products 5 in the evaporating zone an intermediate condensate may be formed and withdrawn as a side stream. This side stream and/or reflux condensate from the primary fractionating zone constitute the immediate source of the intermediate 10 product e. g. Diesel fuel oil or furnace oil. Either or both liquids are introduced into a condensate or Diesel oil flashing zone of reduced pressure, wherein lighter portions thereof are vaporized, the character of the remaining unvaporized oil 15 being determined by the back pressure held on the products in the condensate flashing zone just mentioned. Light products liberated as vapors in the condensate flashing zone are preferably introduced into the secondary fractionating zone 20 in mixture with the lighter constituents from the flashed residue, and therein are similarly separated into relatively light and clean vapors and reflux condensate. These clean vapors are then 25 condensed and introduced into an intermediate point in the primary fractionating zone for further treatment, the products remaining unvaporized in the Diesel oil flash drum being withdrawn and passed through a cooler to storage, as a desired product. 30

The above mentioned and further objects and advantages of my invention and the manner of attaining them will be made clear in the following description and accompanying drawing.

The single figure of the drawing represents 35 schematically an oil treating system embodying my invention.

Referring more particularly to the drawing, fresh charging stock, such, for example, as 34° A. P. I. Mid-Continent gas oil, is introduced 40 through charging line 1, having pump 2, into cracking furnace 3, wherein it is heated to a conversion temperature, which may vary considerably in accordance with known principles. This temperature may be in the range of 800 to 45 1000° F. or more, but is preferably about 850° F., while the pressure maintained on the oil in the furnace may also vary considerably. The outlet pressure on the furnace may be, for example, 100 to 1000 lbs. per square inch, or even higher, 50 but is preferably in the neighborhood of 750 pounds per square inch. The time of passage of the oil through the furnace is preferably great enough to produce a moderate amount of conversion of the oil therein, the highly heated oil 55

passing from the furnace through line 4 into reaction chamber 5 wherein additional conversion takes place, the digested products subsequently passing through line 6, having reducing valve 7, into the lower part of evaporator 8, which is maintained under a lower pressure than that of the reaction chamber, for example, about 200 pounds per square inch. This evaporator is illustrated as having two trap out trays 9 and 10, 10 baffle plates 11, and cooling coils 12 and 13. The introduced products separate into vapors and a liquid residue, the residue being collected in the base of the evaporator, while the vapors pass upwardly. The rising vapors are cooled by action 15 of the cooling coils 12 and 13, through which any cooling medium, such as fresh charge, may be passed in the well known manner, resulting condensate collecting on the trap out trays 9 and 10, while uncondensed vapors pass off from the top of 20 the evaporator through vapor line 14 into a low point in the fractionator or bubble tower 15. A portion of the condensate from trap-out trays 9 and 10 may be directed through line 21 and 20 into the base of fractionator 15, if desired.

25 In the fractionator, which is equipped with bubble trays or any other well known form of fractionating devices, further partial condensation of the vapors takes place, as a result of the cooling action of cooling coil 16 located at the top 30 of the tower. Fresh charge or any other suitable cooling medium may be passed through this coil in the usual manner. Condensate formed in the fractionator is collected in the base thereof, as well as on trap-out trays 15' and 16', if desired, 35 while uncondensed vapors pass off through vapor line 17 and condenser 18, the relatively light distillate being collected in receiving drum 19, having gas draw-off pipe 19'. This distillate is a final desired product such as gasoline, the 40 end point being regulated by proper adjustment of the fluid flow through coil 16 or in any other equivalent manner. Condensate withdrawn from the fractionator through lines 20 or 20', or both, and/or condensate removed from one or 45 both of trays 9 and 10, through line 21, is introduced through line 22, having pressure reducing valve 23, into condensate or Diesel oil flash drum 24, which is maintained at a desired pressure by adjustable relief valve 25 located in the outgoing 50 vapor line 26, which prevents the pressure in the drum 24 from exceeding a predetermined value. The flash drum is equipped with suitable fractionating devices 27, of any well known type, which are adapted partially to fractionate the 55 vapors liberated in the drum, from the introduced products. These vapors pass off through vapor line 26, past the back pressure or relief valve 25, into tar flasher 28, through either of inlets 29 or 30. Residue of a tar like character is withdrawn from the base of evaporator 8 and passed 60 through line 30, having reducing valve 31, into the base of the tar flasher 28, which is maintained at a much lower pressure than that of the evaporator, this pressure being subject to considerable variation, but most suitably being within 65 the limits of atmospheric to twenty-five pounds per square inch.

The resulting flashed vapors, mingled with those entering the tar flasher from pipe 26, rise 70 through the drum and are subjected to fractionation by action of the fractionating devices 32 of any well known type located in the upper portion of the drum and serving as a fractionating zone. A separate fractionating chamber might be provided, if desired for treating the vapors flashed

from the tar in drum 28, and in this case part or all of the fractionating elements in drum 28 could be removed. Vapors remaining uncondensed pass off through vapor line 33, heat exchanger 34, and auxiliary cooler or condenser 35, and are introduced in condensate form into the distillate receiver 36. Distillate so collected is removed through pipe 37 and forced by pump 38, through heat exchanger 34, into an intermediate point in the fractionator 15 or evaporator 8. The point of introduction may be, for example, two trays above the vapor inlet to the fractionator 15.

Branch lines 38 and 39 having respectively control valves 40 and 41 serve to supply refluxing liquid to the Diesel oil flash drum 24, and tar 15 flasher 28, in the order named.

The pressure in the flash drum 24 is maintained at a value somewhat higher than that of tar flasher 28 so that the vapors may flow under their own pressure from the drum to the flasher. The pressure maintained on the flash drum 24, by adjustment of the back pressure valve 25 is held substantially constant by the inherent action of the valve, and is so selected that only sufficient light fractions will be separated in vapor form, 25 from the introduced products, to leave an unvaporized liquid of the desired characteristics, the liquid being withdrawn from the process through draw-off line 42 and cooler 42'. The liquid so withdrawn from the flash drum 24 has the desired 30 characteristics, e. g. those of Diesel fuel oil or furnace oil, any of the undesirable light products present in the condensate withdrawn from the fractionator or from the trap out trays 9 and 10 being removed in the flash drum 24, and returned 35 to the fractionator 15 or evaporator 8, after treatment in the tar flasher 28. If desired the vapors from flash drum 24 may be separately condensed and returned to fractionator 15 as a refluxing medium, valves 50 and 51, pipe 52, condenser 53, 40 receiving drum 54, pump 55 and conduit 56, being provided for this purpose. By closing valve 51 and opening valve 50 all vapors from drum 24 may be directed into condenser 53. If desired condensate may be withdrawn from an intermediate 45 point in the flash drum 24, as a desired product, trap-out trays 24' being provided for this purpose. The condensate so withdrawn may be further stripped if necessary, the resulting vapors being 50 treated similarly to those from line 26 or discarded, while the stripped condensate has the desired characteristics as a final product.

Heavy tar residue may be withdrawn from the tar flasher 28 through draw-off line 43. All or 55 part of the condensate segregating in the bottom of the fractionator 15 may be recycled through line 44, having pump 45, to the cracking furnace 3 for retreatment with the fresh charge. In case all of the condensate is so recycled the products introduced to the Diesel oil flash drum will be 60 withdrawn from either one of the trays 9 and 10 in the evaporator 8, or from trays 15' and 16' in the fractionator 15. The characteristics of the products collecting on the two trays 9 and 10, and the condensate collected in the fractionator 15, 65 may be controlled by proper adjustment of the flow of cooling fluid through the heat exchange coils 12, 13, and 16, as well as by regulation of the amount of refluxing medium supplied. The vapors from the flash drum 24 are preferably introduced into the tar flasher 28 for further fractionation, so that they may be clean enough for introduction into the fractionator 15. However, in certain instances these vapors may be suitable 70 for such introduction without retreatment in the 75

chamber 28, and in this case the vapors may be directed through cross over line 44, having valve 45, and forced directly through the heat exchanger 34, and condenser 35, into the distillate 5 receiver 36.

Other charging stocks than that mentioned may be used if desired, such, for example, as a lighter or heavier gas oil, or other crude distillate. Crude oil might also be so treated, but in that 10 case the amount of cracking carried out on the oil introduced into the evaporator 8 would have to be limited to prevent undesirable carbon formation. The cracking system and the conditions disclosed I consider to be preferable for the charging 15 stock specifically mentioned, but I do not wish to be limited thereto since other cracking apparatus and methods may be used. This process is particularly applicable where a considerable pressure is maintained on the fractionator column 20 15, such, for example, as 200 pounds per square inch, but the invention is also applicable where higher or lower pressures are used, the characteristics of the intermediate product withdrawn from the base of flash drum 24 being controlled 25 by adjustment of the back pressure valve 25. Relatively high pressures on the fractionator 15 are desirable since they keep down the quantity of desirable light gasoline distillate withdrawn from the receiver 19 through the gas draw-off pipe 19', but pressures of a lower value may be used, such as from 40 to 60 pounds per square 30 inch, for example.

While I have described a particular embodiment of my invention for the purposes of illustration it should be understood that various modifications and adaptations thereof may be made within the spirit of the invention as set forth in the appended claims.

I claim:

1. The process of treating hydrocarbon oil which comprises subjecting relatively heavy oil to cracking temperature under superatmospheric pressure to produce conversion thereof, introducing the resulting cracked products into a vapor separating zone wherein vapors separate from liquid residue, cooling said vapors to condense heavier fractions thereof, fractionating the uncondensed vapors in a fractionating zone to produce gasoline, expanding said residue into a first 40 zone of reduced pressure wherein partial vaporization thereof takes place, condensing resulting vapors and introducing condensate so produced into said fractionating zone, expanding the condensed heavier fractions into a second zone of reduced pressure wherein partial vaporization thereof takes place, leaving an unvaporized liquid, introducing resulting vapors into said first zone, and withdrawing said liquid from the process.

2. A process in accordance with claim 1 wherein the pressure of said fractionating zone is in excess of one hundred pounds per square inch, and wherein the pressure in said second zone is adjusted to effect evaporation from said condensed heavier fractions, of sufficient lighter components to give the unvaporized liquid withdrawn from said second zone, the characteristics of ordinary Diesel fuel oil.

3. The process of treating hydrocarbon oil which comprises subjecting relatively heavy oil to cracking temperature under superatmospheric pressure to produce conversion thereof, separating resulting vapors, cooling said vapors to condense heavier fractions thereof, fractionating the uncondensed vapors in a fractionating zone to 70 condense products heavier than gasoline, expand-

ing condensed products into a zone of reduced pressure wherein partial vaporization thereof takes place, removing the unvaporized portion thereof from the process, introducing the vapors of said partial vaporization into a separate flashing zone wherein heavy residue is expanded to 5 separate vaporizable portions therefrom, removing vapors from said separate flashing zone, condensing said vapors, and introducing the resulting condensate into an intermediate point in said fractionating zone.

4. The process of treating hydrocarbon oil which comprises subjecting relatively heavy oil to cracking temperature under superatmospheric pressure to produce conversion thereof, introducing the resulting cracked products into a vapor separating zone wherein vapors separate from liquid residue, cooling said vapors to condense heavier fractions thereof, fractionating the uncondensed vapors in a fractionating zone to produce gasoline, expanding said residue into a first zone of reduced pressure wherein partial vaporization thereof takes place; condensing resulting vapors and introducing condensate so produced, into said fractionating zone, expanding a portion of the condensed heavier fractions into a second zone of reduced pressure, wherein partial vaporization thereof takes place, leaving an unvaporized liquid, introducing resulting vapors into said first zone of reduced pressure, withdrawing said unvaporized liquid from the process as a desired product, and combining another portion of said condenser heavier fractions with said relatively heavy oil for cracking therewith.

5. The process of treating hydrocarbon oil which comprises subjecting relatively heavy oil to cracking temperature under superatmospheric pressure to produce conversion thereof, introducing the resulting cracked products into a vapor separating zone wherein vapors are separated from a liquid residue, partially condensing said vapors in said zone and removing resulting condensate, free from said residue, transferring uncondensed vapors to a fractionating zone wherein heavier fractions are condensed and a desired light product is separated in vapor form and subsequently condensed, removing said liquid residue from said separating zone, introducing the condensate removed from said separating zone directly into a zone of reduced pressure, wherein partial vaporization of said condensate, by its contained heat, takes place, leaving unvaporized liquid oil, preventing the pressure in said zone of reduced pressure from exceeding a predetermined value, removing said unvaporized liquid oil and diverting it from the process as a desired product, passing liquid residue from said separating zone into a tar flashing zone of low pressure wherein partial vaporization of said residue takes place, leaving uncondensed vapors, mingling vapors from the expanded condensate with said uncondensed vapors just mentioned, cooling the resulting vapor mixture to form a condensate and introducing condensate so formed into an intermediate point in said fractionating zone.

6. The process of treating hydrocarbon oil which comprises subjecting relatively heavy oil to cracking temperatures under superatmospheric pressure to produce conversion thereof, introducing the resulting cracked products into a vapor separating zone wherein vapors are separated from a liquid residue, partially condensing said vapors in said zone and removing resulting condensate, free from said residue, transferring un- 70 75

- condensed vapors to a fractionating zone wherein heavier fractions are condensed and a desired light product is separated in vapor form and subsequently condensed, removing said liquid residue from said separating zone, introducing the condensate removed from said separating zone directly into a zone of reduced pressure, wherein partial vaporization of said condensate, by its contained heat, takes place, leaving unvaporized liquid oil, preventing the pressure in said zone of reduced pressure from exceeding a predetermined value, removing said unvaporized liquid oil and diverting it from the process as a desired product, removing liquid residue from said separating zone and expanding it into a tar flashing zone of lower pressure wherein partial vaporization of said residue takes place, leaving uncondensed vapors, mingling vapors from the expanded condensate with said uncondensed vapors just mentioned, cooling the resulting vapor mixture to form a condensate, introducing condensate so formed into an intermediate point in said fractionating zone and combining condensed heavier fractions removed from said fractionating zone with said relatively heavy oil for further cracking.
7. The process of treating hydrocarbon oil which comprises subjecting relatively heavy oil

to cracking temperature under superatmospheric pressure to produce conversion thereof, introducing resulting cracked products into a vapor separating zone wherein vapors are separated from a liquid residue, partially condensing said vapors, leaving uncondensed relatively light vapors, removing said uncondensed vapors and passing them through a fractionating zone to condense undesirably heavy constituents thereof as reflux condensate, removing the fractionated vapors and condensing them as a desired product, returning the reflux condensate for further cracking in mixture with said relatively heavy oil, expanding condensate, formed by the partial condensing step, into a zone of reduced pressure wherein vaporization of the lighter constituents of the condensate takes place, maintaining a substantially constant back pressure on said zone of reduced pressure, removing the unvaporized condensate, and diverting it from the process as a final desired product, removing the vaporized lighter constituents from said zone of reduced pressure, condensing them and combining resulting condensate with said vapors separated from said resulting cracked products for further treatment.

ARTHUR C. HAMPTON.

CERTIFICATE OF CORRECTION.

Patent No. 2,040,048.

May 5, 1936.

ARTHUR C. HAMPTON.

It is hereby certified that error appears in the printed specification of the above numbered patent requiring correction as follows: Page 3, second column, line 23, claim 4, strike out the semicolon after "place" and insert a comma instead; and line 33, same claim, for "condenser" read condensed; same column, line 69, claim 6, for "temperatures" read temperature; and that the said Letters Patent should be read with these corrections therein that the same may conform to the record of the case in the Patent Office.

Signed and sealed this 1st day of September, A. D. 1936.
